UNITED STATES PATENT OFFICE

2,634,615

OSCILLATING MECHANISM FOR WASHING MACHINES AND THE LIKE

Otto J. Voss, Normandy, Mo., assignor to The Simmons National Bank, Pine Bluff, Ark., a corporation of the United States, as trustee

Application August 15, 1949, Serial No. 110,319

7 Claims. (Cl. 74—82)

1

This invention relates generally to washing machines and particularly to an oscillating mechanism therefor.

In the usual washing machine, an agitator is provided within a tub and adapted to be oscillated therein about a vertical axis. The source of motive power for the agitator and other moving parts of the machine is an electric motor or gasoline engine, which delivers its power as unidirectional (when the agitator is being driven) rotation. Since it is not feasible to reverse the direction of the motive power upon each half cycle of agitator oscillation, various mechanisms have heretofore been provided for converting the rotary motion of the source of motive power into the oscillatory rotation of the agitator. For brevity, the mechanisms for converting unidirectional rotary motion into oscillatory rotary motion are herein referred to as oscillating mechanisms. The oscillating mechanisms heretofore provided in washing machines have constituted a source of annoyance, not only to the manufacturer, but to the user, of the machine. The repeated reversal of direction to which the parts are subjected, particularly when under load, results in a constant hammering of the parts together, with consequent wear, loosening, and development of noise.

In the patent to Kuhmann, No. 1,696,718, it was proposed to utilize an adaptation of the familiar "Indian fire stick" principle as the oscillating mechanism of a washing machine, but in the adaptation there disclosed, the device was productive of considerable noise and slap, even when new and properly adjusted, and the magnitude of the noise and slap increased as the parts wore in. Consequently, this type of oscillating mechanism met with no favor in the art.

The object of the invention, generally stated, is to provide a noiseless oscillating mechanism for a washing machine, and one which is not subject to the development of noise during normal use.

Another object of the invention is to provide an oscillating mechanism for a washing machine wherein the parts require no adjustment during use, or because of use.

Other objects will become apparent to those skilled in the art when the following description is read in connection with the accompanying drawings, in which:

Figure 1 is a view in side elevation of a washing machine embodying the oscillating mechanism of the present invention, part being broken away to reveal the relation of the several parts of the machine;

Figure 2 is an enlarged view of the oscillating

2

mechanism, taken in the same elevation as that of Figure 1, with part of the case broken away to reveal the internal parts of the oscillating mechanism;

5 Figure 3 is a sectional view taken along line 3—3 of Figure 2;

Figure 4 is a sectional view taken along line 4—4 of Figure 3;

10 Figure 5 is an inverted perspective view of a bow and stabilizer assembly shown in Figures 2, 3, and 4;

Figure 6 is a perspective view of the stabilizer forming a part of the mechanism shown in Figures 2, 3, and 4;

15 Figure 7 is a view corresponding in part to Figure 3, but showing a different embodiment;

Figure 8 is a partial sectional view taken along line 8—8 of Figure 7;

20 Figure 9 is a perspective view of the stabilizer employed in the embodiment of Figures 7 and 8;

Figure 10 is a view corresponding to Figure 3, but showing a further embodiment of the invention; and

25 Figure 11 is a sectional view taken along line 11—11 of Figure 10.

The present invention envisions a washing machine oscillating mechanism embodying the principle of the "Indian fire stick," the parts of which are so stabilized with reference to each other, and guided in their relative movement, as to be noiseless and free of wear despite the constant reversal of direction during operation. The word "noiseless" is used herein in the practical sense as indicating that the noise resulting from normal operation is not perceptible to the unaided ear. By "free of wear," as the expression is herein used, is meant that the parts are subject to so little wear that the useful life of other parts of the machine is exhausted before the mechanism concerned.

30 I have discovered that noiseless operation and freedom from wear in the oscillating mechanism of a washing machine may be accomplished with an "Indian fire stick" type of mechanism if means be provided to assure that the line of pull

45 is at all times tangential to a circle of fixed radius concentric with the agitator axis. The invention, therefore, contemplates the provision of stabilizing means whereby, irrespective of the direction of movement at any increment of time, and irrespective of the position of the parts at any increment of time, the line of pull is tangential to the same circle (but not at the same radius of that circle).

50 55 Referring now to Figures 1 to 6, inclusive, for

an illustrative embodiment of the invention, the washing machine is provided with a source of motive power, such as an electric motor 1 connected by a belt 2 to a pulley 3, which latter drives the oscillating mechanism encased in a casing 4 and preferably running in lubricant. The casing 4 is mounted upon the frame of the machine below a tub 5, within which is contained the usual agitator or dolly 6. The agitator 6 oscillates on a vertical shaft 7, the latter being driven by the oscillating mechanism now to be described.

As shown clearly in Figures 2 and 3, the pulley 3 is secured to a shaft 8, which extends through appropriate bearings in casing 4, and on the interior of the casing is provided with a worm 9. The worm 9 meshes with a worm wheel 10 mounted for rotation upon a vertical shaft 11. The worm wheel 10 is provided with a crank-pin 12 arranged to receive a bow member 13. The bow member 13 provides spaced anchorages 14 and 15 for the connection of the free ends of two roller chains 16 and 17, respectively.

On the agitator shaft 7, two sprockets 18 and 19, of a pitch and conformation to interfit with the chains 16 and 17, respectively, are mounted in a manner such as to drive the agitator shaft 7. The end of chain 16 remote from anchorage 14 is wrapped in one direction about sprocket 18 and secured thereto by a pin 20 extending through a lug 21 on the sprocket 18. Likewise, the end of chain 17 remote from anchorage 15 is wrapped in the opposite direction about sprocket 19 and secured thereto by a pin 22 extending through a lug 23 on the sprocket 19. The pitch diameter of the sprockets 18 and 19 is so chosen that, at the extreme positions, one or more teeth of the sprockets, in addition to the lugs 21 and 23 thereof, as the case may be, are engaged with rollers in the respective chains 16 and 17, so that at no time is the entire load sustained by the pin-and-lug connections above described.

The invention is particularly concerned with eliminating the tendency, during movement, for the bow 13 to assume positions of differing radial displacement from the center of shaft 7. In order to maintain the radial displacement (by which is meant the radial distance between the bow and the center), a stabilizer 24 is mounted for pivotal movement concentric with shaft 7 and arranged to slide in a slot 25 extending lengthwise of bow 13, as clearly shown in Figures 4 and 5. In the embodiment shown, the stabilizer 24 is T-shaped, having a mounting leg provided with an aperture 26 adapted to be received on shaft 7 and have a running fit therewith. At the opposite extremity, the stabilizer 24 is provided with a blade 27 having a thickness such as to be received in slot 25 of bow 13 and have a sliding fit therein. The length of the stabilizer 24, from the axis of hole 26 to blade 27, is carefully controlled so that, when blade 27 is seated in slot 25 of bow 13, a straight line passing through the pin centers of the straight portions of the chains 16 and 17 and the center of crank-pin 12 will be tangent to the pitch circle of sprockets 18 and 19. Some variation from tangency to the pitch circle may be tolerated provided, at all times in its cycle of movement, the bow 13 is tangent to the same circle, i. e., maintained at fixed radial displacement from the center of shaft 7. The interconnection provided between the bow 13 and shaft 7 by stabilizer 24 assures this.

In the embodiment shown in the drawings, the casing 4 and its companion lid 40 perform the

function not only of encasing the parts and keeping them sealed in lubricant, but also of maintaining the several parts in assembled relation. The shaft 11 is mounted in a boss 41 and secured against rotation therein by a nut 42. In accordance with a common practice, the shaft 11 is provided with an eccentric portion 43 whereby the worm gear 10 may be adjusted into proper relationship with the worm 9. The worm wheel 10, however, rotates freely upon shaft 11 and is held in position thereon within the casing 4 by the arrangement of parts now to be described.

The crank-pin 12 is mounted in a hole of proper size in worm wheel 10 as, for example, by press-fitting the parts together. Surrounding the crank-pin 12, the worm wheel is provided with a boss 44 constituting a seat against which the knuckle boss 45 of bow 13 may be pressed with a suitable washer 46 intervening, if desired. The outer end of crank-pin 12 is reduced in diameter, as shown at 47, forming a shoulder 48 on the crank-pin just inwardly of the outer extremity of boss 45 on the bow 13. A spring washer 49 is arranged upon the reduced portion 47 of crank-pin 12 and surmounted by a fiber annulus 50, which extends slightly beyond the outer extremity of reduced portion 47 on crank-pin 12. The fiber annulus 50 is proportioned in axial dimensions so that, when lid 40 is applied to the casing 4, the fiber annulus 50 will be pressed against the action of spring washer 49, thus pressing boss 45 toward the worm wheel, and the worm wheel toward the opposite side of casing 4. The inner surface of lid 40 is provided with a raceway 51 annular in shape and substantially concentric with shaft 11. The race-way 51 has the surface thereof, which is exposed for contact with the fiber annulus 50, finished in such manner as to have good sliding properties with reference to fiber annulus 50, which moves thereabout under the pressures of spring washer 49. If desired, the race-way 51 may be formed of different material from that of lid 40 and suitably anchored thereto so as to provide a sliding path for the end of fiber annulus 50.

With the arrangement of parts just described, no nuts, pins, keys, or other fastenings are required to hold the bow 13 and the worm wheel 10 in properly assembled relation within casing 4. The lid 40 is secured to the casing by suitable bolts, or otherwise, and such attachment maintains the aforesaid parts in their proper assembled relation. The pressure of spring 49 is exerted wholly between annulus 50 and boss 45. The reaction from the former is received by lid 40, while the reaction from the latter is received by the bottom of casing 4 through the intervention of washer 46 and worm wheel 10.

A further embodiment is shown in Figures 7, 8, and 9 wherein, in lieu of the bow and stabilizer in the form above described, the stabilizer and bow are formed integrally, as shown in Figure 9. In this embodiment, the bow 130 has a boss 131 for connection with crank-pin 12, and is provided with anchorages 134 and 135 for connecting the ends of chains 16 and 17.

The bow 130 is provided with a flange 132 having an elongated slot 133, whose width is such as to be received over agitator shaft 7 and have a running fit therewith. The displacement between the center of slot 133 and the anchorages 134 and 135 is regulated so that, as in the previous embodiment, the straight portion of the chain is tangent at all times to a circle of fixed radius concentric with shaft 7.

A further embodiment is shown in Figures 10 and 11, in which, in contrast to the previous embodiments, the rectilinear portion of the drive chain is not fixedly stabilized so as to be tangent with the desired circle, but is resiliently so stabilized. In this embodiment, the shaft 7 is provided with a roller 107 freely running thereon. The outer periphery of the roller 107 engages a flat 108 on bow 113. Thus the engagement between the roller 107 and bow 113 positively prevents movement of the bow 113 in a direction so as to reduce the radial displacement from the center of axis 7 below a predetermined value controlled by the radius of roller 107. In order to assure the maintenance of the proper radial displacement in this instance, however, a spring-biased roller 114 is provided for engagement with a flat 109 on the opposite side of bow 113 from roller 107. In the embodiment shown, the roller 114 is mounted upon the free end of a cantilever spring 115. In this, as in the previous embodiments, the dimensions of the parts are so chosen that the rectilinear portion of the chains will at all increments of time during operation be tangent to a circle of given radius and be in straight-line relation with the axis of crankpin 12.

In the apparatus shown in Figures 1 to 9, inclusive, the oscillating mechanism operates efficiently, noiselessly, and without wear in the practical sense.

While, in the embodiment shown in Figures 10 and 11, the radial displacement between the bow and the agitator shaft is not fixed, the tension exerted by the spring thereon may be sufficient to maintain this displacement sufficiently constant for practical purposes and, when the tension of the spring is sufficient to maintain the constant displacement, the operation is almost as noiseless as with the other embodiments.

Utilizing the oscillating mechanism shown in Figures 1 to 6, inclusive, a test run of 1700 hours' washing time was carried out with the machine under load. The power consumption utilizing the oscillating mechanism of the present invention was approximately seventy-five percent of the power consumption of the same machine equipped with conventional oscillating mechanism and, at the end of such run, the oscillating mechanism of the present invention was as noiseless as at the beginning and showed no perceptible signs of wear or looseness.

From the foregoing description those skilled in the art should readily understand that the present invention accomplishes its objects and provides an oscillating mechanism for washing machines, which is not only noiseless and free from wear, but cheap to manufacture and dependable in operation. While three complete embodiments of the invention have been disclosed in detail, it is not to be understood that the invention is limited to those embodiments but, on the contrary, that the principles thereof may be adapted and applied by numerous forms and arrangements of parts consistent with the principle that the bow be caused to travel at fixed radial displacement from the center of the oscillating shaft. Consistent with that principle, such modifications and variations as present themselves to those skilled in the art are contemplated by and within the scope of the appended claims.

Having thus described the invention, what is claimed and desired to be secured by Letters Patent is:

1. In an oscillating mechanism for a shaft comprising a rotatable crank, a bow connected to said crank for operation thereby, and tension members extending from said bow and wrapped about said shaft; the combination of spacing means cooperating with said bow and said shaft for maintaining constant radial distance between said shaft and said bow.
2. The combination of claim 1 wherein the spacing means comprises a part mounted on said shaft for concentric rotation relative thereto, said part interengaging said bow and relatively slidably lengthwise thereof.
3. The combination of claim 1 wherein the spacing means comprises an extension on the bow having a slot extending in a direction lengthwise of the bow, said slot being received on said shaft and rotatable relative thereto.
4. The combination of claim 1 wherein the tension members are anchored to said bow in spaced relation lengthwise thereof and wherein the anchorages are aligned rectilinearly with the connection between said crank and said bow.
5. In an oscillating mechanism for the agitator shaft of a washing machine, a casing having separable sections, means for connecting the sections together, a shaft mounted in one of the sections, a crank mounted on said shaft and having an eccentric pin arranged to move about an orbit concentric with said shaft, a pitman journaled on said pin, a slide bearing on said pin outwardly of said pitman, overlapping the latter, and engaging the opposite one of said casing sections, and the last mentioned one of said casing sections having an annular slideway for said bearing conforming to the orbit of said pin.
6. The combination of claim 5 wherein the slide bearing is fiber and a spring washer is interposed between said pitman and the fiber bearing.
7. In an oscillating mechanism for a shaft comprising, a rotatable crank, a bow connected to said crank for operation thereby and tension members anchored at spaced points to said bow, said tension members being wrapped about said shaft between said points of anchorage, the improvement which comprises, said points of anchorage being located on a straight line with the connection between said bow and said crank, and means for maintaining said straight line in tangent relation with and at a fixed radial distance from the center of said shaft.
